UNITED STATES PATENT OFFICE.

JAMES JONES FAULKNER, OF JACKSON, MICHIGAN, ASSIGNOR TO THE NATIONAL COTTON SEED OIL AND HULLER COMPANY, OF MEMPHIS, TENNESSEE.

MACHINE FOR DELINTING COTTON-SEED.

SPECIFICATION forming part of Letters Patent No. 430,843, dated June 24, 1890.

Application filed December 28, 1889. Serial No. 335,181. (No model.)

To all whom it may concern:

Be it known that I, JAMES JONES FAULKNER, a citizen of the United States, and a resident of Jackson, in the county of Jackson and State of Michigan, have invented certain new and useful Improvements in Machines for Delinting Cotton-Seed, of which the following is a specification.

My invention relates to machines for removing the lint from cotton-seeds. Its object is to rapidly remove the lint without breaking the kernels.

The invention will be first fully described in connection with the accompanying drawings, and will then be particularly pointed out in the claims.

In the accompanying drawings, in which like parts are indicated by similar reference-letters wherever they occur throughout the different views, Figure 1 is a central transverse vertical section of a machine constructed according to my invention. Fig. 2 is a front elevation of the same upon a reduced scale, having a portion of the casing broken away through line $x x$ of Fig. 1 to expose the parts back of it; Fig. 3, a detail view in end elevation upon the same scale as Fig. 1, the sprocket-wheels being cut off by a section taken vertically through their shafts. Fig. 4 is a detailed view upon an enlarged scale of part of the cylinder and the check-plate, showing means for adjusting the latter vertically. Fig. 5 is a detailed view upon an enlarged scale of a portion of one of the feed-rolls perforated to receive the feed-pins.

The cylinder A is secured upon a shaft B, which has its bearings in the supporting uprights or end standards C. The exterior of the cylinder is, for lightness, preferably formed of wooden staves a, which are secured upon the rim of the armed wheels or spiders a', keyed upon the shaft B. The surface of the cylinder A is covered with sand-paper, emery or card cloth, sand, concrete, or similar rough or scouring material a², to which the lint will adhere. The cylinder is inclosed in an outer shell formed by wooden end pieces D and a sheet-metal cover fastened around their edges;

or, if preferred, the outer case may be of wood.

Upon one side of the case D is formed a segmental chamber D', the outer wall of which is concentric with the axis of the cylinder A. The top of this chamber is provided with a hopper or feed-spout d, located at one end of chamber D', through which the seed is fed to the machine and carried into contact with the surface of cylinder A by a series of feed-rolls E. The shafts e of these rolls have their bearings in flanged metal hubs e', which are secured to the ends of the chamber D' by screws passing through their flanges. Upon the projecting ends of these shafts are secured sprocket-wheels e². A similar wheel b' is secured upon the cylinder-shaft B. The feed-rolls are all driven in the same direction by a sprocket-chain F, which passes around the wheels b' e². The tension of the sprocket-chain is regulated by an idle-sprocket e³, carried by an arm e⁴, which is pivoted upon a stud-bolt secured in the end of the case, as shown in dotted lines in Fig. 1.

The feed-rolls are provided with pins which are preferably arranged upon spiral lines to carry the seed from the feed to the discharge end of the chamber D'. The seed-discharge is a grated opening, as seen at d², Fig. 2, at the end of the chamber diagonally opposite from the feed, the interstices of the grating being just large-enough to permit the seeds to pass after they are freed from lint and from one another, as they will be when the lint is removed.

The upper end of the chamber D is provided with a check-plate I, which is preferably made vertically adjustable, as by having its securing-bolts I⁷ pass through slots I⁶ therein, as in Fig. 4. Its lower edge is set a sufficient distance from the cylinder to allow the lint from the seed to be carried around on the cylinder to the lint-discharge chamber D, where it is stripped from the cylinder and thrown out through the discharge-spout by the revolving brushes G. The brush-shaft g extends through the end of the lint-discharge chamber, and has secured upon it a pulley g',

driven by a band which passes over a pulley b^2 , secured upon the end of the cylinder-shaft B.

The chamber D', is for convenience, made 5 separate from the cylinder-casing and hinged to it at II, so that by throwing off the sprocket-chain F and disengaging the fastening-hook h the chamber, with its feed-rolls, may be turned down for the purpose of replacing the sand-paper or other scouring material used upon 10 the cylinder when it becomes worn.

The operation of the machine is as follows: Seed, being fed into the chamber D', is carried by the toothed rolls to the scouring-surface 15 face of cylinder A. The tendency of the feed-rolls is to carry the seed down toward the bottom of the chamber D, while the tendency of the cylinder A is to carry them in the opposite direction. So long as any lint adheres 20 to the seed they hang together, so that the teeth of the feed-rolls will hold on to them and continuously at each revolution bring them in contact with the rough stripping-surface of the cylinder; but so soon as the lint 25 is removed they will be released from the teeth of the rolls and will not adhere to the cylinder, but drop by gravity to the bottom of the chamber D' and be discharged through the grated discharge-opening.

30 I have shown and described what I believe to be the best form of my invention; but I do not limit myself to the exact forms shown, as many structural changes will readily occur to those skilled in this branch of the art. I 35 shall therefore consider such mere mechanical modifications as within the spirit and scope of my invention as herein claimed.

I claim—

1. The combination of the supporting-frame, 40 the cylinder having its surface coated with sand-paper or similar material mounted to

revolve therein, the outer casing inclosing said cylinder and having the feed-roll chamber D', the toothed roll fitted to revolve in said chamber, the check-plate to prevent the seed 45 being carried to the lint-discharge chamber, the revolving brush to strip the lint from the cylinder and discharge it from the machine, and means for driving the cylinder, brush, and feed-rolls, substantially as shown and 50 described.

2. The combination of the cylinder A, having the surface-coating a^2 , the case inclosing said cylinder, the chamber D', having hopper d and grated discharge d^2 hinged to one side 55 of said casing, the lint-discharge chamber D^2 at the opposite side, the feed-rolls E, mounted to revolve in chamber D, the brush-cylinder G in the lint-discharge chamber, and the plate I to prevent the seed from passing to the 60 lint-discharge chamber, substantially as shown and described.

3. The combination, substantially as described, of the supporting-frame, the linting-cylinder, the case inclosing the same, the 65 lint-discharge chamber at one side of said case and the feed-chamber at the opposite side provided with a hopper and seed-discharge chamber, the feed-rolls mounted to revolve in the feed-chamber in proximity to 70 each other and to the cylinder, the feed-roll shaft extending outside of said chamber, the sprocket-wheels secured upon said shafts, the sprocket on the cylinder-shaft and sprocket-chain F for driving the feed-rolls, the brushes 75 in the lint-discharge chamber, the brush-shaft g, pulley g' , pulley b' on the cylinder-shaft, and the belt to drive the brush.

JAMES JONES FAULKNER.
